US00D844579S

(12) **United States Design Patent** (10) **Patent No.:** **US D844,579 S**
(45) **Date of Patent:** **** Apr. 2, 2019**

(54) **TELEVISION APPARATUS**

(71) Applicant: **LG ELECTRONICS INC.**, Seoul (KR)

(72) Inventors: **Huisik Kim**, Seoul (KR); **Hodong Hwang**, Seoul (KR)

(73) Assignee: **LG ELECTRONICS INC.**, Seoul (KR)

(**) Term: **15 Years**

(21) Appl. No.: **35/503,815**

(22) Filed: **Apr. 12, 2017**

(80) **Hague Agreement Data**

Int. Filing Date: **Apr. 12, 2017**

Int. Reg. No.: **DM/095752**

Int. Reg. Date: **Apr. 12, 2017**

Int. Reg. Pub. Date: **Oct. 13, 2017**

(30) **Foreign Application Priority Data**

Oct. 18, 2016 (KR) 30-2016-0049932

(51) **LOC (11) Cl.** **14-03**

(52) **U.S. Cl.**

USPC **D14/126**
